UNITED STATES PATENT OFFICE.

BYRON J. SNYDER, OF AMSTERDAM, NEW YORK, ASSIGNOR TO CHALMERS KNITTING COMPANY, OF AMSTERDAM, NEW YORK, A CORPORATION OF NEW YORK.

UNDERGARMENT.

1,187,019.

Specification of Letters Patent. Patented June 13, 1916.

Application filed January 29, 1912. Serial No. 673,966.

To all whom it may concern:

Be it known that I, BYRON J. SNYDER, a citizen of the United States, residing at Amsterdam, county of Montgomery and 5 State of New York, have invented certain new and useful Improvements in Undergarments, of which the following is a specification.

The invention relates to such improvements and consists of the novel construction 10 and combination of parts hereinafter described and subsequently claimed.

Reference may be had to the accompanying drawings, and the reference characters 15 marked thereon, which form a part of this specification.

Similar characters refer to similar parts in the several figures therein.

Figure 1 of the drawings is a view in 20 front elevation of a combination undergarment embodying my invention. Fig. 2 is a view in rear elevation of the same. Fig. 3 is a view in front elevation of the same with the front of the garment broken away 25 from the crotch up, to show the flap construction for protecting the crotch-opening. Fig. 4 is a view in rear elevation of the same with the rear of the garment broken away from the crotch up, to show the manner in 30 which the mutually lapping flaps close the front opening of the garment. Figs. 3 and 4 are drawn on a larger scale than Figs. 1 and 2.

This invention relates to undergarments 35 of various kinds, and I have shown the invention embodied in its preferred form in a combination undergarment having an open crotch.

Certain objects of the invention are to 40 provide an undergarment with a properly protected liberal crotch-opening; to secure proper fitting of the crotch portion of the garment; and to relieve the pull of the crotch portion of a close-fitting undergar- 45 ment, and particularly of a combination undergarment.

Other objects will appear in connection with the following description.

In the application of my invention to an 50 undergarment having an open crotch, such as a combination or union garment, I protect the crotch-opening by mutually lapping flaps which extend from front to rear around the crotch, each having a free edge

extending from a point at one side of the 55 middle of the back of the garment to a point at the same side of the middle of the front of the garment.

Referring to the drawings wherein the invention is shown in preferred form, 1, is 60 the body of a combination undergarment provided with a front opening extending part way only to its crotch, and adapted to be closed by button-connected front flaps, 2 and 3, in the usual manner; and 4 and 5, 65 are, respectively, inner and outer gores or flaps which extend from front to rear around the crotch of the garment, said flaps preferably lapping each other uniformly throughout their length. At the front of 70 the garment these lapped flaps are secured to the body of the garment by a seam, 6, extending across the lower end of the front opening to permanently close the same; and said flaps are connected by a seam, 7, along 75 their outer edges to the body of the garment along the opposite sides of the crotch-opening which they are intended to fill and protect, said connecting seam, 7, extending down to points in the respective legs, 8, of 80 the garment. The flaps 4 and 5, are shown adapted to lap each other uniformly throughout their length. The inner edge, 9, of the flap, 4, is free from the body of the garment from a point, 10, on the left- 85 hand side of the back of the garment whereat it leaves the seam, 7, to a point, 11, on the left-hand side of the front of the garment whereat it leaves the seam 6. In like manner the inner edge, 12, of the flap, 5, 90 is free from the body of the garment from a point, 13, on the righthand side of the back of the garment whereat it leaves the seam, 7, to a point, 14, on the right-hand side of the front of the garment whereat it leaves the seam 6. The points, 10 and 13, are equidistant from the middle of the back, and the points, 11 and 14, are equidistant from the middle of the front of the garment. It is not necessary, therefore, for 100 either of the flaps, 4 and 5, to assume a forced position to fill and protect the crotch-opening; but, when the garment is held vertically, these flaps naturally fall into a mutually lapping position, entirely filling 105 and protecting the crotch-opening.

The crotch-opening can be exposed by drawing the flaps, 4 and 5, apart; and, as

the flaps are symmetrically disposed and the right-hand and left-hand portions of the crotch of the garment are symmetrical, said flaps can be so separated with minimum pull 5 upon the legs or body of the garment.

In the use of a combination garment, unless the garment is made of ample length from the shoulder to the crotch, the crotch-portion of the garment will exert an uncomfortable pull upon the wearer. A similar pull may be experienced with a nether garment unless it is made of ample length from the crotch to the waist-line whereby the garment is supported. One of the features of this invention contemplates the overcoming of this objectionable feature of close-fitting undergarments by providing the garment with a back-gore made of fabric highly elastic longitudinally of the garment 10 as compared with its elasticity transversely of the garment, and as compared with the elasticity of the body of the garment longitudinally. With a back-gore so made extending upward from the crotch of the garment, the yielding of the gore-fabric vertically or longitudinally of the garment will relieve the pressure at the crotch, even when the garment is somewhat scant in length, and will also relieve pressure at the crotch 15 which would otherwise result from strained positions of the wearer even though the garment fit properly in normal positions of the wearer.

I have shown the body of the garment 20 made of knitted fabric with the wales extending longitudinally or vertically, whereby the garment is rendered highly elastic horizontally or transversely, and I have shown as a preferred construction each of 25 the gores or flaps, 4 and 5, formed of a front gore-piece, 4^a or 5^a, made of knitted fabric with the wales running vertically or longitudinally, and a rear gore-piece, 4^b or 5^b, made of knitted fabric with the wales extending horizontally or transversely, the 30 gore-piece, 4^a, being secured to the gore-piece, 4^b, by a seam, 15, and the gore-piece, 5^a, being secured to the gore-piece, 5^b, by a seam 16. The seams, 15 and 16, are located 35 approximately at the crotch of the garment, the gore-pieces, 4^b and 5^b, extending upward from the crotch at the back of the garment. For certain purposes of the invention, however, said gores or flaps may be made of any 40 desired material in any known manner.

Where parts of the garment have been shown in cross-section in Figs. 3 and 4, a single ply only of fabric has been shown, and no attempt has been made to show the

facings with which the flap-portions of the 60 garment are provided in the usual manner.

In the preferred form of my invention the garment, while having an open crotch with the advantages pertaining thereto, has a closed-crotch effect, the open crotch being 65 filled and inclosed by the mutually lapping flaps.

What I claim as new and desire to secure by Letters Patent is—

1. A combination undergarment having 70 an open crotch, and provided with a front opening extending part way only to the crotch, and having a pair of mutually lapping flaps extending from front to rear around the crotch and closing the lower end 75 of said front opening, each of said flaps having a free edge extending from a point at one side of the middle of the back of the garment to a point at the same side of the middle of the front of the garment, and at 80 one side of said front opening, the body of said garment and the front portion of said flaps being made of knitted fabric with the wales extending longitudinally of the garment, and the back portion of said flaps being 85 made of knitted fabric with the wales extending transversely of the garment.

2. A garment having an opening therein and a flap arranged to cover said opening, said flap having its upper portion and a longitudinal edge secured to the body of the garment and having a longitudinal free edge and comprising two fabric sections secured together along their adjoining edges with the wales of one section extending cross-wise and the wales of the other extending lengthwise of the garment, whereby the flap is rendered elastic in all directions. 90

3. A garment having an opening therein and a flap arranged to cover said opening, 100 said flap having its upper portion and a longitudinal edge secured to the body of the garment and having a free longitudinal edge and comprising an upper fabric section with the wales thereof extending cross-wise of the garment and a lower fabric section having its upper edge secured to the upper section and having the wales thereof extending lengthwise of the garment, whereby the flap is rendered elastic in all directions. 105

In testimony whereof, I have hereunto set my hand this 22nd day of January, 1912.

BYRON J. SNYDER.
